UNITED STATES PATENT OFFICE.

BERNARD HARTLEY PETER, OF WESTMINSTER, ENGLAND, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA.

SIGNALING SYSTEM.

1,286,401.

Specification of Letters Patent.

Patented Dec. 3, 1918.

Application filed October 7, 1914. Serial No. 865,495.

To all whom it may concern:

Be it known that I, BERNARD HARTLEY PETER, a subject of the King of Great Britain, residing at 58 Victoria street, in the city 5 of Westminster, England, have invented certain new and useful Improvements in Signaling Systems, of which the following is a specification.

This invention relates to railway signaling systems of the kind in which an alternating 10 electric current for signaling purposes is supplied to circuits constituted by the track rails from any suitable source, such for instance as an alternating current generator or 15 a transformer supplied thereby.

In systems of the above kind, the track rails are usually divided into block sections, the rails of which are arranged to be short-circuited as regards the signaling current 20 supplied thereto when the section is occupied by a train, the actuation of one or more of the signaling devices being arranged to be effected in any desired manner by this means so as to indicate the presence of a 25 train in the block section.

In order to enable both rails of the track to be employed as the return circuit for propulsion current in the case of an electrically 30 propelled railway, it is usual to cross-connect the track rails at each end of the block section by inductive devices known as inductance bonds, the middle or other intermediate points in the windings of each bond being connected to a corresponding point in 35 the winding of the bond in the next adjacent block section.

The function and operation of these inductance bonds is now well known and need not be further described, but it will be understood 40 that the winding of the bond serves as a direct electrical connection between the two track rails as regards direct current, but while maintaining the two rails at different alternating current potentials for signaling 45 purposes.

In order that the reactance of the inductance bonds may be as great as possible as far as alternating currents are concerned, it has previously been proposed to provide the 50 bonds with a continuous magnetic circuit or core thus enabling a magnetizing current of relatively small amount to create a large magnetic flux in the core of the bond owing

to its low magnetic permeability, thereby insuring a sufficiently high reactive electro-motive force. This construction is however open to the disadvantage that the direct propulsion current passing through the winding of the bond is also capable of creating a large magnetic flux owing to the low reluctance of the continuous magnetic core and although the direct currents flowing in the two parts of the winding of the bond on either side of the middle or intermediate point above referred to are in opposite directions, any unbalancing of the current in the two track rails will necessarily cause a magneto-motive force to be set up which in view of the low reluctance of the magnetic circuit of the bond may easily cause magnetic saturation of the core. If this condition occurs, the bond will evidently cease almost entirely to respond to the alternations of the signaling electro-motive force and only a very small amount of reactive 70 electro-motive force will be developed in the winding of the bond which is thus rendered inoperative for the purpose for which it is intended.

In order to overcome this disadvantage 80 it has also been proposed to provide the magnetic circuit of the bond with an air gap so as to reduce its permeability and thereby prevent magnetic saturation as above described. This construction, however, is open 85 to the further disadvantage that the permeability of the magnetic circuit of the bond is reduced for alternating current magnetization also and consequently a considerably increased magnetizing alternating current is 90 necessary which must evidently be supplied from the source of signaling current. As the magnetizing current is almost entirely wattless, it represents a very unfavorable load on the alternating current generator or other 95 source of signaling current and the present invention has for its object to provide an improved arrangement whereby inductance bonds having air gaps in their magnetic circuits may be employed without at the same 100 time imposing a load of low power factor upon the source of signaling current.

According to the present invention the circuit of the bond is arranged to be inductively related to a resonant circuit that is to 105 say to a circuit containing such an amount

of capacity or condensance relative to its inductance that a condition of resonance is partly or completely obtained.

In the accompanying drawings:

5 Figure 1 is a diagrammatic view of a portion of two block sections, the adjacent ends of the different sections being bridged by means of impedance bonds;

10 Figs. 2, 3 and 4 being similar views illustrating various embodiments of the invention.

15 It will be understood that these embodiments of the invention are merely illustrative of various ways by means of which the invention can be carried into practice and are not to be regarded as restricting the scope of the invention to any of the arrangements shown.

20 Referring first to all of the views, the reference characters 1, 2 designate the track rails of a railway, which rails are divided by insulated joints 9 to form block sections in the usual and well known manner. Alternating signaling current is supplied to the 25 rails of each block section from a suitable source such as a generator G. It being understood that both of the track rails are included in the circuit for the propulsion current, the rails are cross-connected at each 30 end of each block section by an impedance or inductance bond (designated 3 in Fig. 1 and 4 in Figs. 2, 3 and 4), the middle point of each bond being connected to the middle point of the adjacent bond in the next section by a conductor 10; the function and operation of these bonds are so well understood in the art as to require no explanation herein. In one embodiment of the invention the terminals of the inductance bond 35 4 are connected to the primary winding 5 of a transformer (see Fig. 2) the secondary winding 6 of which is closed on itself through a condenser 7, the capacity of the condenser being such that the inductance of the whole circuit including the primary and 40 secondary windings of the transformer and the inductance bond constitute with the condenser a resonant circuit. The wattless component of the magnetizing current required for the bond will thus be constituted 45 by the resonant currents surging into and out of the condenser in the well known way and the only current required to be supplied to the track circuit will be that corresponding 50 to the true watts loss in the track rails and the inductance bonds.

55 In the alternative construction as illustrated in Fig. 3, the inductance bond 4 itself may constitute the necessary transformer, 60 the magnetic circuit of the bond being provided with a secondary winding 8 the terminals of which are connected through the condenser 7, a separate transformer being thus unnecessary.

65 In the arrangement illustrated in Fig. 4

the condensers 7 are shown connected in parallel with each inductance bond.

70 It will be understood that the ratio of the number of turns of the primary and secondary windings of the transformer, where such is employed, or between the number of turns in the winding of the bond and in the secondary winding of its core, may be varied as desired, the object of the transformer or of the bond acting as a transformer, being to 75 reduce the capacity of the condenser required by increasing the voltage impressed on its terminals.

76 Furthermore the amount of capacity or condensance employed may if desired be 80 such as to exceed that corresponding to the inductance of the bond so as to enable the circuit of the bond to take a leading current and thereby compensate for the inductance of the other parts of the circuit such for instance as the track rails themselves.

85 The actual system of connections employed may evidently be varied from those above described without exceeding the scope of the invention.

90 What I claim is:—

1. In a railway signaling system the combination of a block section, a source of signaling current connected across the track rails of said block section, an inductance bond also connected across said track rails and a condenser electrically associated with said bond for supplying the wattless component of the current taken by said bond.

95 2. In a railway signaling system the combination of a block section, a source of signaling current connected across the track rails of said block section, an inductance bond also connected across said track rails and means associated with the bond which 100 takes a wattless current leading the voltage.

105 3. In a railway signaling system the combination of a block section, a source of signaling current connected across the track rails of said block section, an inductance bond also connected across said track rails and means associated with said bond for 110 producing current resonance therewith.

115 4. In a railway signaling system the combination of a block section, a source of signaling current connected across the track rails of said block section, an inductance bond also connected across said track rails and an auxiliary circuit electrically associated with the winding of said bond and 120 containing a condenser of sufficient capacity to produce resonance in combination with the inductance of said bond and its direct connections.

125 5. In a railway signaling system the combination of a block section, a source of signaling current connected across the track rails of said block section, an inductance bond also connected across the said track rails, and a local circuit inductively related 130

to said bond for supplying the wattless component of the current taken by said bond.

6. The combination in a railway signaling system of an inductance bond, a winding in 5 inductive relation to such bond and a condenser directly connected across the terminals of said winding.

7. An inductive bond for electric railway track circuits constituting a plurality of insulated track sections, comprising a primary winding the terminals of which are adapted 10 for connection to the two rails of a track section, a tap at the mid-point of the primary

winding for interconnecting adjacent track sections to one another, a secondary winding 15 magnetically linked with the primary winding, and a condensive reactance element connected in closed circuit with the secondary winding.

In testimony whereof, I have signed my 20 name to this specification in the presence of two subscribing witnesses.
